UNITED STATES PATENT OFFICE.

FRANK D. REYNOLDS AND JOSEPH SACHS, OF HARTFORD, CONNECTICUT, ASSIGNORS TO THE SACHS COMPANY, OF HARTFORD, CONNECTICUT, A CORPORATION OF CONNECTICUT.

THERMAL CUT-OUT.

No. 926,962.

Specification of Letters Patent.

Patented July 6, 1909.

Application filed January 7, 1908, Serial No. 409,628. Renewed December 12, 1908. Serial No. 467,221.

To all whom it may concern:

Be it known that we, FRANK D. REYNOLDS and JOSEPH SACHS, citizens of the United States, residing at Hartford, county of Hartford, Connecticut, have invented certain new and useful Improvements in Thermal Cut-Outs, of which the following is a full, clear, and exact description.

Our improvement relates to thermal cut-outs and has for its object to produce a new and improved thermal cut-out which shall have superior advantages in construction and operation.

Heretofore the fusible members of safety fuses have been constructed of metallic strips having a rounded or rectangular section. In order to prevent hanging of the fusible strip or wire of inclosed fuses, when molten, it has been suggested that the strips be made of very thin metal for producing a maximum area of contact with the filling and of radiating surface, and consequently rendering the dispersion of the molten metal easy and reducing the amount of metal required in the fuse strip for a certain carrying capacity. Such strips, aside from being fragile, would be of excessive widths when used with loose or granular fillings, necessitating casings or tubes of undesirably large diameter and have, therefore, never been used commercially with such fillings. It has also been found that by subdividing the conductor into a number of parallel conductors connected in multiple to common terminals at their ends, similar results would accrue, but such arrangements, aside from possessing objections similar to those already stated, are in addition more or less complicated and possess inherent difficulties of manufacture and accurate operation.

The primary object of our invention is to produce a fusible conductor for safety fuses, whether they are exposed or inclosed, which will by its inherent construction reduce the amount of metal required for a fuse of a certain carrying capacity and yet eliminate the objection to the fuse strips of thin metal or the composite multiple conductors made up of a number of small conductors in parallel. To obtain this result we construct a single fusible conductor of any desired carrying capacity of limited spread in any radial or diametric sectional direction, but yet of very large superficial surface or cross sectional outline. That is, the sectional outline or

boundary is serrated, notched, indented, star-shaped or radially flanged or spoked so that the spread or extension of the conductor, sectionally, is limited, but at the same time the sectional outline is very large in relation to the sectional area, therefore not only producing the results already stated but also possessing the following advantages: The strip employed has greater rigidity for a given amount of metal and is, therefore, easier to handle; it has a great radiating surface relatively to the metal contained in it. It always has an elongated section of metal which is not in a horizontal plane so that the attraction of gravitation will more readily cause the strip when fused to materially change its shape. Moreover, when molten, the parts will be acted upon more strongly by molecular attraction tending to draw them toward the center and thus assist in the disruption of the fuse. There will also be unequal strains in the parts of the strip when heated which will cause it to break down as desired. It can be readily calibrated. When used in inclosed fuses it has, in addition to the advantages above mentioned, a large surface in contact with the filling and is widely distributed throughout the filling, and utilizes all portions of the filling, being substantially equidistant from the walls of the casing on all sides. While this improved construction may be used for either open or inclosed fuses, it is particularly desirable in the latter.

The following is a description of an embodiment of our invention, reference being had to the accompanying drawings, in which—

Figure 1 is a partial longitudinal section of an inclosed fuse embodying our invention; Fig. 2 is a cross section of the same on the line $x-x$ Fig. 1; Fig. 3 is a partial longitudinal section of one end of an inclosed fuse embodying a modification of our invention; Fig. 4 is an enlarged section of the fuse strip of Fig. 3 on the line $y-y$ of Fig. 5; Fig. 5 is a plan view of the strip in Fig. 3; Fig. 6 shows a fuse strip similar to that shown in Fig. 1, with a modified calibration cut; Fig. 7 is another modification of the fuse strip showing a slightly different form and another form of calibration cut; Fig. 8 is a modification of the fuse strip of Fig. 1, showing twice as many projections.

Referring more particularly to the drawing, A is a fuse strip, preferably of zinc, which

21
 in the preferred form is surrounded by a casing B and a loose filling C, as in ordinary enclosed fuses. The strip A is of such shape that its cross section presents a serrated outline, by which is meant an outline having alternate projections and indentations. The projections are shown as pointed, but obviously that is not necessary, since other forms of projections may be used. The strip A is 5 connected to split terminals A' of harder metal of higher conductivity, such as copper, which are preferably soldered thereto, the strip being forced into the split end. In the forms shown, these split conductors are connected to blade terminals D which enter 10 through the caps E of the tubular case B, the parts being secured by screws F—F' and reinforcing plates F².

While fuse strips constructed as thus far 15 described operate successfully on overload and short circuit, it is desirable to provide at some point along the length of the strip (preferably the center) a portion of attenuated or decreased section so as to further insure the 20 rupture of the conductor at that point when molten, and thus eliminate any molten hanging, or the maintenance of electrical continuity while the metal is in a molten condition. Such attenuation may be provided by notch- 25 ing or perforating the strip with so-called calibration notches or holes, which further serve to accurately fix the blowing point of 30 the strip, and in Fig. 1 is provided by the notches G. Fig. 6 shows a section of the fuse strip A on an enlarged scale with a calibration hole G' through its core. Fig. 7 shows a 35 similar fuse strip having a cross section in the form of a three-pointed star with calibration holes G² in the wings. Fig. 8 shows a similar 40 fuse strip having a cross section in the form of a six-pointed star with calibration notches G³. Fig. 9 shows a strip in the form of a series of projections H on a flat base I, with 45 calibration notches G⁴, connected to terminals A² and blades D² and inclosed in a tubular casing B' with filling C'. In all these forms the apexes of the projections are substantially in the form of a circle, that being

the preferred construction, so as to have the strip equally distributed on all sides through the filling and equally distant from all parts of the tube or casing. When the form shown in Fig. 3 is used, the extreme ends of the strip 50 may be soldered or otherwise joined to the disks J at the ends of the terminals A². 55 These constructions admit of various modifications in form and proportions without departing from the spirit of our invention. The sectional area of the strip relatively to the sectional area of the casing is somewhat 60 enlarged over what it would be in practice, this being necessary in order to clearly show the construction.

What we claim is:

1. A fuse strip of serrated cross-sectional outline. 65
2. A fuse strip of serrated cross-sectional outline, the spaces between the projections being substantially equal, the extremities of said projections lying substantially in a circle. 70
3. A fuse strip having angularly disposed, radially projecting and longitudinally extending flanges. 75
4. In a fuse, the combination of a fuse strip whose cross-section has a serrated form, a casing inclosing said strip and a filling within said casing. 80
5. In combination, a fuse strip whose cross section has a serrated form, the extremities of the projections lying substantially in a circle, a tube inclosing said strip and a filling within said tube. 85
6. In combination, a fuse strip of serrated cross-sectional outline, an inclosing case, filling material in the case and around the strip and terminals between which the strip is connected. 90
7. A fuse strip of serrated cross-sectional outline having an attenuated cross-sectional area for a portion of its length. 95
